UNITED STATES PATENT OFFICE.

WILLIAM E. ELLIOTT, OF GRAND RAPIDS, MICHIGAN, ASSIGNOR TO AMERICAN BUTTON & FASTENER COMPANY, A CORPORATION OF MAINE.

MOUNT AND METHOD OF MOUNTING LACING-HOOKS.

1,291,810.

Specification of Letters Patent.

Patented Jan. 21, 1919.

Application filed January 17, 1916, Serial No. 72,649. Renewed May 20, 1918. Serial No. 235,696.

To all whom it may concern:

Be it known that I, WILLIAM ELLIOTT, a citizen of the United States of America, residing at Grand Rapids, in the county of Kent and State of Michigan, have invented certain new and useful Improvements in Mounts and Methods of Mounting Lacing-Hooks; and I do hereby declare the following to be a full, clear, and exact description of the invention, such as will enable others skilled in the art to which it appertains to make and use the same.

This invention relates to the packaging of small articles such, for example, as lacing hooks of the types employed upon shoes, gloves, and the like, and while the illustrated embodiment of the invention is directed to a package containing lacing hooks of the type employed upon shoes, it will be understood that the invention is not so restricted.

An important object of the invention relates to a method of packaging small articles such as lacing hooks, arranged in a series upon an elongated strip, preferably of flexible material, which is particularly designed to render the strip with its attached articles more flexible when it is desired to coil the same into a package.

Another object of the invention relates to a package of lacing hooks in which the lacing hooks are conveniently arranged and temporarily retained in a novel and improved manner.

A feature of the invention consists in the arrangement of a package of lacing hooks such that the lacing hooks are temporarily attached to an elongated strip, for example, by passing the shanks thereof through the strip, and are temporarily retained therein by bending over one edge of the strip so that it enters the recesses between the heads and the shanks of the lacing hooks. Such a package enables the retention of lacing hooks in a predetermined relation to one another so that they occupy a comparatively small amount of space and may be formed into a compact package from which they may be removed without disturbing the relationship between the series of hooks.

Other features consist in a construction and arrangement of a package of lacing hooks such that the package is rendered

more flexible by the removal of specified portions of the mounting strip.

Other features of the invention will appear from the following description of an illustrative embodiment of the invention, taken in connection with the accompanying drawing, in which—

Figure 1 is a perspective view illustrating a completed package containing lacing hooks.

Fig. 2 is a plan view thereof.

Fig. 3 is a transverse section on the line 3—3 of Fig. 2; and

Fig. 4 shows a development of a mounting strip to which lacing hooks may be attached previous to the folding of the strip more securely to retain the hooks thereon. Figs. 1, 2 and 4 show but a fragment of a strip of indefinite length to which the hooks are secured.

Like reference characters refer to like parts throughout the several views of the drawing.

Lacing hooks commonly comprise a shank or barrel 1 at the upper end of which is formed the hook proper consisting of an overhanging head 2 above and connected by a neck to a base 3 which lies directly against and is formed integrally with the upper end of the shank. The mount to which hooks of this character are to be attached is, preferably, of thin flexible material such as paper or the like which may be considered to consist of an intermediate section 4 preferably having a plurality of circular holes 5 formed therein into which the shanks 1 of the hooks extend, an outer section 6 at one edge of the mount, a back section 7 which is adapted to be turned up to cover the necks of the hooks and a second outer section 8 adapted to be turned over the heads of the hooks as shown in Fig. 3.

After the shanks of the hooks have been inserted through the strip as, for example, by being passed through the openings, 5, the paper is bent on the dotted lines indicated at *a* and *c* so that the section 6 overlies the base part 3 of the hooks and enters the recesses between the heads and shanks thereof. The strip is also bent on the lines *e* and *g* as indicated in Figs. 1 and 3 so that the rear section 7 lies directly back of the hooks and

the section 8 bends over the hooks and contacts with the heads 2 thereof, the hooks in this manner being securely retained in predetermined relationship against displacement.

Slots 9 and 10 are cut in the mounting strip at intervals, the former transversely of the rear section 7 and slightly into the section 8, and the latter at the bend between sections 4 and 6 of the mount. These slots preferably are located between the positions occupied by the hooks so that after the hooks are positioned in place on the mount as shown in Figs. 1, 2 and 3, the whole may be easily wound into a coiled package, the removal of the paper at 9 and 10 permitting the bending of the material of the mount which otherwise would buckle and resist the forming of the mount and attached hooks into such a package. It is to be understood that the strip may be and usually will be of great length and will contain a very large number of hooks located one after another in a single row, and that, for purposes of transportation and handling, it may be found desirable to coil the mount with the attached hooks so as to make a compact package.

I claim:

1. In combination, a strip of thin material provided with a plurality of openings, a plurality of lacing hooks having parts passing through said openings in the strip, said hooks being positioned in a row one after the other and a section of the strip at one side bent inwardly and entering the recesses between the heads and shanks of said hooks.

2. In combination, a strip of thin material having a plurality of openings spaced apart and located lengthwise of the strip, a plurality of lacing hooks positioned on the strip with parts of the hooks entering the openings in the strip, and a section at one side of the strip bent upwardly back of the hooks and then over the tops of said hooks.

3. In combination, a strip of thin material having a plurality of openings therein, a plurality of lacing hooks having shanks passing through said openings in the strip, said hooks being located in a row one after another, a section of the strip at one side bent inwardly and entering the recesses between the heads and shanks of said hooks; and a section at the other side of the strip bent upwardly back of the hooks and then over the heads of said hooks.

4. In combination, a strip of thin flexible material having a plurality of openings therein, a plurality of lacing hooks having shanks passing through said strip, said hooks being positioned in a row one after another, and a section of the strip at one side bent inwardly and entering the recesses between the heads and shanks of said hooks, said strip at the bend thus made having

parts removed to permit the rolling of the strip and attached hooks into a package.

5. In combination, a strip of thin flexible material having a plurality of openings therein, a plurality of lacing hooks having shanks passing through said openings in the strip, said hooks being positioned in a row one after another, a section of the strip at one side bent inwardly and entering the recesses between the heads and shanks of said hooks, and a section at the other side of the strip bent upwardly back of the hooks and then over the heads of the hooks, said strip at one of the bends thus made in it having parts removed to render the same more flexible.

6. In combination, a mount for lacing hooks comprised of a member having openings therein, lacing hooks having portions thereof entering said openings, and means on the mount entering the recesses between the heads and shanks of said hooks thereby to hold the hooks on said member.

7. In combination, an elongated strip, a plurality of lacing hooks arranged in a series along said strip and temporarily attached thereto, one side of said strip being bent inwardly and arranged to enter the recesses in said hooks.

8. In combination, an elongated strip, a plurality of articles arranged in a series and temporarily attached to said strip, said strip being bent over a portion of each of said articles and portions of said strip being removed adjacent to the bend therein to render the strip more flexible when it is desired to form the same into a package.

9. In combination, an elongated strip, a plurality of articles temporarily attached thereto and arranged in a series along said strip, the edges of the strip being turned over said articles and portions of the strip being removed along the sides of the turned over portions to render the strip more flexible and permit rolling the same into a package.

10. In combination, an elongated strip, a plurality of lacing hooks temporarily attached to said strip in a series and having the shanks thereof inserted in the strip, the strip at one side of the lacing hooks being bent inwardly to enter the recesses between the heads and shanks of the hooks and the other side of the strip being bent upwardly over the heads of the hooks, said strip having portions removed from the sides of the bent over portions of the strip to render the same more flexible when it is rolled into a package.

11. A method of mounting lacing hooks upon an elongated strip which consists in passing the shanks of the hooks through said strip and arranging them in similar positions in a series along said strip, and then bending over one edge of the strip and ar-

ranging it within the recesses between the heads and shanks of the hooks.

12. A method of mounting small articles upon an elongated strip which consists in forming a plurality of openings in said strip along a line substantially parallel to one side thereof, temporarily attaching the articles thereto at one side of said row of openings,

and then bending the strip over a portion of said articles along the line of the openings 10 so that the openings will fall in the side of the turned over portion and will render the strip more flexible when it is desired to roll the same into a package.

In testimony whereof I affix my signature. 15
WILLIAM E. ELLIOTT.
